UNITED STATES PATENT OFFICE.

GEORGE MCKERAHAN, OF PITTSBURGH, PENNSYLVANIA.

JET-OPERATED AIR COMPRESSOR.

Application filed October 8, 1921. Serial No. 506,407.

To all whom it may concern:

Be it known that I, GEORGE MCKERAHAN, a citizen of the United States, residing at Pittsburgh, in the county of Allegheny and State of Pennsylvania, have invented new and useful Improvements in Jet-Operated Air Compressors, of which the following is a specification.

This invention relates to air compressors 10 of the type in which a jet of water or steam is used as the compressing agent.

In existing compressors of this class the combination of an adequate air supply and a confined true piston action is lacking so 15 that only a small part of the compressing fluid's energy is utilized. The present improvement aims at placing large bodies of air directly in the path of the jet with only a slight interruption of the current; at the 20 same time both the air and the compressing fluid, during their whole passage, are confined so as to obtain an effective piston action of the compressing agent.

These results are accomplished by causing 25 air filled tubular chambers to pass in rapid succession across the path of the jet and by making the jet nozzle of a transverse area and outline closely conforming to the like area and outline of each of the tubular 30 air chambers of the wheel. The tubes are assembled about a central shaft on which they rotate at high speed. This assembly of 35 revolving tubes may be termed an air charging wheel and will be so referred to in this specification.

In the accompanying drawing Fig. 1 shows a vertical longitudinal section through the stationary casing which incloses the charging wheel and also through the compression cylinder and discharge pipe in which the casing terminates. This section exposes a full side view of the charging wheel. Fig. 2 is a plan view of the compressor, the compression cylinder at the 40 right being broken away; at the jet end a part of the casing is removed exposing the 45 interior of a portion of one of the wheel channels and showing the manner in which the jet is delivered to it. Fig. 3 is an end 50 view of the jet end of the compressor, the bearing stand and jet nozzles being removed and the casing support not shown; and Fig. 55 5 is a face view of the upper nozzle. Fig. 5 shows on a reduced scale a sectional view of a slightly different design of the compressor which is explained later.

Identical numbers refer to the same parts throughout the several views;

A stationary cylindrical casing 1 has a tapering end 2 which converges to the compression cylinder 3 and terminates in an enlarged discharge pipe 4. Closely fitting the interior of stationary casing 1—2 is a revolving air charging wheel 5 the small end of which terminates at the entrance to compression cylinder 3. The large jet end of wheel 5 is supported by shaft 6 which rotates in bearing 7. A shaft 8 which supports the small end of the air charging wheel extends through compression cylinder 3 to a bearing 9, the latter being attached to the interior of discharge pipe 4 by radial ribs which afford free passage between them for the fluids. Shaft bearing 9 for this end of the charging wheel is carried beyond cylinder 3 so as not to obstruct the latter. Air charging wheel 5 consists of channels 10 placed closely together and concentric with the wheel's shaft; in conjunction with the closely fitting stationary casing 1 these channels form tubes to which the air and compressing fluid are confined laterally. Stationary nozzles 11 and 12 deliver the jets of water or steam to channels 10 as the latter revolve before the nozzles. As seen in Fig. 3, channels 10 are oblong in cross section their longest sides being nearly radial; their separating walls 13 are made quite thin and at the jet end the wall faces are reduced to a knife edge as shown. This construction 50 will offer very slight obstruction to the current as walls 13 pass across the jet. The transverse area and outline of each of jet nozzles 11 and 12 are made to conform to the like area and outline of each of air 55 chambers 10 as may be seen in Fig. 4, all corners of the nozzles being slightly rounded. By this construction the jet is converted into a series of closely fitting pistons, backward leakage of the air is prevented 60 and a higher degree of compression is obtained.

Channels 10 are given a helical direction along the axis of the wheel as shown in Fig. 1, thereby causing the impact of the jets to 65 give rotation to the wheel. In large compressors rotation may be given by a belt on pulley 17 shown in dotted lines in Fig. 2. In this case the helical direction of channels 10 would preferably be retained in water jet 70 compressors, so as to avoid giving a revolving motion and injurious centrifugal action 110

to the water pistons. But when the wheel in a steam-jet operated compressor is rotated by a pulley or other external means, the helical form of the air chambers need not be used, but the chambers may be disposed straight and lengthwise around the shaft, because the low specific weight of steam will be only slightly affected by centrifugal action.

10 A single jet may be used for all sizes of compressors, but the use of two which discharge into opposite channels of the wheel, as shown in the drawing, will afford a balanced and more effective delivery to compression cylinder 3, besides allowing the use of a smaller charging wheel for equal capacity. For very large compressors three or four jets may be used.

20 The volume of air placed before each water or steam piston will depend on the axial length of the charging wheel, while the speed of the wheel will determine the quantity of water or steam delivered to each air charge; thus exact adjustment of air 25 charge and jet delivery may be made so as to obtain the best result.

30 At the small end of wheel 5 some of the channel walls 13 may be removed for a short distance as shown so as to prevent undue constriction of the passages.

Discharge pipe 4 would be connected to a separating receiver which is not shown.

35 In the design shown in Fig. 5 the charging wheel 5 is tightly fitted within its casing 14 and the latter revolves with the wheel. The wheel joins stationary compression cylinder 3 by a revolving joint 15 which fits within the expanded end of cylinder 3 as shown. Parts broken away are the same as in Fig. 1. 40 The drawing shows the circumference of the air charging wheel and its casing to be in part cylindrical and having tapered ends, but if preferred the taper may extend the entire axial length of the wheel in both designs.

45 The air charging wheel of this compressor would have a speed of one to two thousand revolutions per minute, approximately.

By making suitable connections the machine may also be used as an exhauster.

I am aware that a jet operated blower has

been devised in which the jet, by impact upon the blades, gives rotation to a fan of the ordinary propeller type and thereby causing the fan to give blower movement to the air.

What I claim as new is:

1. In a jet operated air compressor, tubular air chambers disposed around a central shaft on which they revolve, the length of the tubular chambers lying in the direction of the shaft's length, and the transverse outline and area of said tubular chambers conforming respectively to the like outline and area of the jet nozzles, each to each; one or more stationary jet nozzles which discharge into an end of the revolving tubular air chambers; the opposite end of the chamber wheel converging to a single compression tube which connects to a discharge pipe; and a pulley or other means attached to the shaft of the air chamber wheel by which the wheel is rotated.

2. In a jet operated air compressor, tubular air chambers disposed helically around a central shaft on which they revolve, the transverse outline and area of said tubular chambers conforming respectively to the like outline and area of the jet nozzles, each to each; one or more stationary jet nozzles which discharge into an end of the revolving tubular air chamber; the opposite end of the chamber wheel converging to a single compression tube which connects to a discharge pipe; and a pulley or other means attached to the shaft of the air chamber wheel by which the wheel is rotated.

3. In a jet operated air compressor, tubular air chambers disposed helically around a central shaft on which they are revolved by impact of the jet upon the helical chamber walls; one or more jet nozzles which discharge into an end of the revolving air chambers, the transverse outline and area of said nozzles conforming respectively to the like outline and area of the said tubular air chambers, each to each; and the opposite end of the chamber wheel converging to a single compression tube which connects to a discharge pipe.

GEORGE MCKERAHAN.
